Brown & Woodward

UNITED STATES PATENT OFFICE.

FERDINAND Q. HARTMAN, OF DANVILLE, PENNSYLVANIA.

THREAD-BREAKING DEVICE FOR SPINNING MACHINES.

Application filed April 14, 1920. Serial No. 373,750.

To all whom it may concern:

Be it known that I, FERDINAND Q. HARTMAN, a citizen of the United States, and resident of Danville, in the county of Montour and State of Pennsylvania, have invented a new and useful Improvement in Thread-Breaking Devices for Spinning Machines, of which the following is a specification.

- 10 This invention relates to a thread breaking device for spinning machines and more particularly to a thread breaking device which may be applied to spinners for independently spinning a plurality of threads 15 and winding the threads so spun on a single spool, from which latter the threads are subsequently to be twisted into one strand on a twisting machine. It is quite essential in an operation of this kind, that a single 20 thread, or a less number than the whole number of threads being wound, be not allowed to run onto the spool, as this would produce a serious defect when the threads so spun were finally twisted into a strand.
- 25 My present invention is directed to a thread breaking device which may be interposed between the spindles and the take-up spool on which the spun threads are wound, and which shall be under the control of each of the thread guide levers to perform its function of breaking a companion thread when another thread is unintentionally broken, so that the several threads may be united before any one or 30 more of the threads has or have been allowed to be wound upon the take-up spool without its or their companion thread or threads.

The object of the invention is to provide a device of this character which is 40 relatively cheap and simple in construction while positive in action.

Another object consists in providing such a device which has means for automatically locking the thread breaking mechanism in 45 inoperative position.

Another object consists in providing certain means, form, construction and arrangement of the several parts whereby the above named and other objects may be effectively 50 attained.

A practical embodiment of my invention is represented in the accompanying drawings, in which

Fig. 1 represents a front elevation of one

of the devices in operative position, so much 55 of the spinning machine being shown as will suffice to disclose a practical application of my invention.

Fig. 2 represents a vertical section taken in the plane of the line II—II of Fig. 1, 60 looking in the direction of the arrows.

Fig. 3 represents a detail section of the parts of the thread breaking device proper, parts being shown in different positions in 65 full lines and dotted lines, and

Fig. 4 represents a similar view of the parts shown in another position.

The main frame of the machine on one end is denoted by 1, the take-up spool by 2, the traverse guide for removing the threads and laying them on the take-up spool, by 3, the wheel for driving the take-up spool by 4 and a pair of spindles for spinning two independent threads, by 5 and 6, the bobbins carrying the threads on the spindles 5 and 6, are denoted by 7 and 8. The threads which lead from the respective bobbins 7 and 8 are denoted respectively by 9 and 10. For the purpose of supporting the thread breaking mechanisms in proper position on the 70 spinning machine so that there shall be one for each group of threads to be combined on a single take-up spool, I secured a horizontal rail 11, to the end frame 1 of the spinning machine. This rail may be composed of 75 wood so as to receive a screw 12 for attaching the brackets containing the thread breaking mechanism in position. Each bracket consists of a face plate 13 which has two forwardly projecting arms 14, 15, each of which arms has in addition a laterally projecting wing 16, 17, and oppositely disposed stops 16*, 17*.

A pair of thread guide levers 18, 19 are pivoted in the lower part of the arms 14, 15 80 by a pintle 20, and limited in their outward movement by the stops 16*, 17*.

The thread guide levers 18, 19 are provided with feet (one of which is shown at 21, Figs. 2, 3 and 4), which project rearwardly substantially at right angles to the main body portion of the said levers and the balance of the parts is such that the weight of the said feet 21 causes the levers to be under a normal tendency to swing or drop 85 rearwardly. Each of the said guide levers 18, 19 has a guide wire 22 fixed to its upper parts by means of a screw 23. The upper 90

end of these guide wires are bent laterally in the form of a hairpin and arranged to receive the threads.

The thread breaking mechanism proper 5 consists of an arm 24 which is pivoted on the pintle 20 between the levers 18, 19 and which has a weight 25 for overbalancing it so as to cause it to normally rest in substantially horizontal position and out of the way of 10 the threads running from the bobbins 7 and 8 as clearly shown in Fig. 2. In this position the arm 24 impinges against the lower part of the face plate 13 of the bracket.

The said arm 24 has a pair of laterally extending lugs 26 which are adapted to be 15 engaged by the foot 21 of the thread guide levers 18, 19, when one of the latter falls or drops rearwardly, for the purpose of overbalancing the arm 24 and swinging it against 20 the resistance of its weight 25, into approximation to the threads running to the bobbins 7, 8, as will hereinafter be described.

The extremity of the arm 24 opposite the 25 weight 25 is furnished with a thread breaking mechanism which consists of a crosshead 27 provided with a thread catching coil 28 at each end thereof. This crosshead may be composed of wire suitably bent and coiled into shape and it may conveniently be secured to the arm 24 by bending it around 30 ears 29 formed thereon. The device also includes guide and tension elements which have coiled body portions 30, 31 and upwardly extending hook-shaped stems 32, 33. 35 These combined the guide and tension elements may appropriately be composed of wire coil and bent into proper shape, and they are secured to the wings 16, 17, of the brackets by means of screws 34, 35. It is, 40 intended that the thread shall be passed through one or more of the coils of the body portions 30, 31 and then wound around the stems 32, 33, one or more times in order to give the desired tension, as clearly shown in 45 Figs. 1 and 2.

In order to hold the thread guide levers 18, 19 substantially motionless and out of engagement with the arm 24, during the spinning and winding of the thread, guide 50 bars 36, 37 are mounted in a bracket 38 carried by the rail 11. The location of these guide bars are such that, when the thread guide levers 18, 19 are in thread guiding position with their guide wires 22 engaged by 55 the threads 9, 10, the said guide wires will lie between the two bars, while the thread passes in front of the said bars. It will be apparent that this arrangement tends to hold the levers 18, 19 snugly up against the bars 60 36, 37, during the operation of the machine, while the said bars also impart a slight additional tension to the thread, owing to the balance of the guide levers 18, 19, and tends to cause them to fall rearwardly as already described.

Means is also provided for temporarily locking the thread guide levers and counterbalanced arm 24 in the position shown in Fig. 2, or the thread guide levers locked in one position and the arm 24 in its operative 70 position as shown in Fig. 4. This means includes a shaft 39 which is journaled in an ear 40 uprising from the bracket 38. A detent 41 is fixed to the shaft by a set screw 42 and a handle 43 is formed by bending one end of the shaft 39. The detent is provided with oppositely disposed lugs 44, 45 which are arranged to engage cam faces 46 of the thread guide levers 18, 19 for locking them in an inoperative position as shown 80 in Fig. 4. The counterbalanced arm is locked by means of a finger 47 projecting upwardly from the detent 41 in position to engage the weight 25 in either the position shown in Fig. 4 or the position shown in 85 Fig. 2, in which latter position the detent is shown in dotted outline. Thus, it will be seen that the detent with its lugs and finger will lock both the thread guide levers and the arm 24 in withdrawn or inoperative position. When it is desired to lock the thread guide levers and the arm in inoperative position, it is simply necessary to turn the handle 43, and hence the shaft 39 and the detent carried thereby, into position so 90 that the finger 47 engages the weight 25 and the lugs 44, 45 engage the cam faces of the thread guide levers 18, 19. When the parts are locked in either of the positions above described, the thread may be disengaged from 95 either or both of the thread guide levers. 100

In operation the thread which comes from the bobbins 7, 8 is passed through the coils 30, 31 and around the stems 32, 33 of the combined guide and tension elements, thence through the guide wires 22 and thence over the traverse guide 3 and under the spool 2. If, during the operation of the machine, one of the threads 9, 10 accidentally breaks, the guide lever with which it is engaged 105 will at once drop back so that its foot contacts with the lug 26 on the arm 24 and thereby overbalances the latter against its weight 25 so as to cause it to swing down into the position shown in Figs. 3 and 4, in which position one of its coils 28 will at once be engaged by the unbroken thread whirling about, whereby the said thread will 110 be broken and thus prevent a length of single thread from being wound upon the 115 spool 2.

The subject matter of this invention is shown and described but not claimed in my co-pending applications, Serial No. 237,600, filed May 31st, 1918, Serial Nos. 373,748 and 120 373,749, filed April 14th, 1920.

It will be understood that various changes may be resorted to in the form, construction and arrangement of the several parts without departing from the spirit and scope of 125 130

my invention, and hence I do not intend to be limited to the details herein shown and described except as they may be specifically included in the claims.

5. What I claim is:

1. The combination with a thread breaking mechanism for spinning machines comprising, a counterbalanced thread breaker, of a coil carried by said thread breaker arranged to be swung by the breaker into the path of the thread to catch and break the thread.

10. 2. The combination with a thread breaking mechanism for spinning machines comprising, a counterbalanced thread breaker, of oppositely disposed coils carried by said

thread breaker arranged to be swung by the breaker into the path of the threads to catch and break them.

3. The combination with a thread breaking mechanism for spinning machines comprising, a counterbalanced thread breaker provided with an arm and laterally extending ears, of a cross head bent to engage said ears and having coils arranged to be 20 25 swung by the breaker into the path of the threads to catch and break them.

In testimony, that I claim the foregoing as my invention, I have signed my name this 22nd day of March, 1920.

FERDINAND Q. HARTMAN.
